UNITED STATES PATENT OFFICE

2,248,246

OVERHEAD SPRING SASH-BALANCE

Royal R. Moss and George B. Knapp, Los Angeles,
Calif., assignors to Nelle Frances Kersting, Los
Angeles, Calif.

Application June 7, 1939, Serial No. 277,766

4 Claims. (Cl. 20—11)

Our invention relates generally to sash balances of the type employing a sheet metal housing containing a drum or drums, with a coil spring disposed within said drum and a metal tape or cable adapted to wind onto and from the periphery of the drum, with one end of said tape or cable connected to the window sash.

Such forms of spring sash balances form the subject matter of U. S. Letters Patents No. 1,733,666, issued October 29, 1929, and No. 1,762,821 issued June 10, 1930, also the spring sash balance forming the subject matter of copending patent application filed November 8, 1937, Serial No. 173,421.

It is the general practice to install the spring sash balances of the type to which our invention relates, in openings formed in the jambs of window frames and, it is the principal object of our invention to construct the sash balances and particularly the housings thereof so that the balances may be easily and conveniently installed in the header or rail between the upper portions of the jambs of the window frame, thus providing overhead installations which in many instances are entirely feasible and desirable.

A further object of our invention is, to construct the sash balance housing and particularly the face plate thereof so that it may be conveniently applied to the under side of the header of the window frame with the body of the housing projecting upwardly through an opening in the header and with one end of the face plate or an extension that projects from the end of the housing, resting on the jamb at the lower end of the notch or opening that is formed therein for the reception of the end of the header.

A further object of our invention is, to provide a base or anchor plate for that portion of the face plate or the extension from the housing that enters and rests upon the jamb below the end of the header.

With the foregoing and other objects in view, our invention consists in certain novel features of construction and arrangement of parts that will be hereinafter more fully described and claimed and illustrated in the accompanying drawing in which:

Fig. 1 is an elevational view of a spring sash balance installed in the window frame as an overhead balance and showing portions of the header and jamb in section.

Fig. 2 is a horizontal section taken approximately on the line 2—2 of Fig. 1.

Fig. 3 is a cross section taken on the line 3—3 of Fig. 2.

Fig. 4 is a perspective view of the plate that is applied in the bottom of the header receiving notch of the jamb and which provides a support for the projecting end of the face plate or other member that projects from the sash balance housing.

Fig. 5 is a detail elevational view showing a modified form of the means utilized for supporting the sash balance in the frame.

Fig. 6 is a vertical section taken through the lower outer corner of a sash balance housing and showing a modified form of the supporting means therefor.

Fig. 7 is a vertical section taken on the line 7—7 of Fig. 6.

Fig. 8 is a vertical section similar to Fig. 6 and showing a further modified form of the support for the housing.

Fig. 9 is a detail section taken on the line 9—9 of Fig. 8.

Fig. 10 is a vertical section taken on the line 10—10 of Fig. 8.

Referring by numerals to the accompanying drawing, and particularly to the construction illustrated in Figs. 1 to 4 inclusive, 10 designates the jamb of a window frame and which in accordance with established practice is notched or mortised on its inner face, as designated by 11, for the reception of the end of the lintel or header 12 of the window frame.

For the accommodation of the spring sash balance housing or housings H, an opening 13 is formed in the lintel, said opening extending longitudinally from the end of the lintel that enters the mortise or notch 11 and, the length of said opening being slightly greater than the width of the sash balance housing.

The sash balances contemplated by our invention are generally of the type forming the subject matter of the above mentioned Patents No. 1,733,666 and No. 1,762,821 and co-pending application for patent, Serial No. 173,421, each balance including a rotatably mounted spring-held drum on which is adapted to wind a thin, flat, metal tape or cable C that extends downwardly from the housing and, its lower end being suitably connected to the upright side rail or lower corner of the window sash.

Each sash balance housing H is provided with a face plate 14, preferably formed of sheet metal, and when the housing is properly installed this face plate lies directly against the under face of the lintel 12 with the housing H projecting upwardly through opening 13. A portion of this face plate 14 at the outer end thereof projects

beyond the end of the housing a distance equal to the depth of the notch or mortise 11 and, due to this projecting portion of the face plate the opening 13 that receives the housing H must be formed slightly longer than the housing, in order that the latter when applied to the lintel may be moved upwardly through opening 13 and thence longitudinally of the lintel so as to bring the outer end of the face plate 14 flush with the outer end of said lintel and with the outer end portions of both lintel and face plate positioned in the mortise or notch 11.

In order to provide a firm and substantial base for the support of the end of the face plate that projects into the mortise, an anchor plate 15, preferably a metal strap, is positioned on the bottom of the mortise 11 and is secured thereto in any suitable manner, preferably by means of a nail or screw 16 that passes through an aperture 17 in the center of the base plate.

Portions of the base plate between the center and ends thereof are depressed to form pockets 18 that receive the projecting portions of the face plate 14 and the depth of which pockets is equal to the thickness of the face plates (see Fig. 4).

When the housing including the face plate is applied to the lintel that portion of the face plate that extends inwardly from the notch or opening 13 is secured to the lintel, preferably by means of a screw 19 that passes through the projecting portion of the face plate and upwardly into the lintel. Thus when the spring sash balance is properly applied for use, it is firmly secured to the lintel and projects upwardly through an opening immediately adjacent the jamb with which the lintel is associated and the flexible metal tape or cable C extends downwardly through an opening in the face plate immediately adjacent the jamb and, the lower end of said cable is connected in the conventional manner to a window sash.

In Fig. 5 we have illustrated a modified arrangement for supporting the sash balance housing on the shoulder formed at the lower end of the mortise in the jamb and, in this construction a substantially L-shaped bracket 20 has its vertical leg rigidly fixed, preferably by spot welding, to the lower portion of the end of the sash balance housing H and, the horizontal leg of this bracket projects outwardly in the same plane with the face plate 14 and rests on the base plate 15 that is positioned on the bottom of the mortise 11 in the jamb.

In the modified construction illustrated in Figs. 6 and 7, the upper portion of a flat spring formed from a narrow piece of resilient metal 21 is rigidly secured by spot welding or rivets to the inner face of the end wall of the sash balance housing that is positioned adjacent the jamb 11 and, the lower portion of this resilient strip is bent into a horizontal plane to form a foot 22 that extends outwardly through a slot 23 in the lower portion of the end wall of the housing and said foot is adapted to rest on the base plate 15 at the lower end of the mortise in the jamb.

Cut and stamped from the lower portion of the resilient member 21 just above the foot 22 is a depending lip 24 which passes through the opening 25 that accommodates the metal tape or cable of the sash balance and, this lip is adapted to be engaged and moved inwardly away from the end wall of the housing so as to flex member 21 and draw the foot 22 into said housing when the

latter is installed in the lintel or when the lintel and housing are removed from the jamb.

In the modified construction illustrated in Figs. 8, 9, and 10, a narrow strap 26 of metal is arranged for sliding movement on top of the face plate below the end wall that is positioned adjacent the jamb and, said strip is retained for such sliding movement by an overlying plate 27 of sheet metal, the edges of which are suitably secured to the upper surface of the face plate. When the strip 26 is drawn inwardly, the sash balance housing may be readily inserted through the opening in the lintel and when said strip is moved outwardly as illustrated in Fig. 8, its outer portion rests on the anchor plate 15 at the bottom of the mortise in the jamb.

The sliding strip, the overlying plate 27, and the face plate of the sash balance housing, are provided with coinciding apertures 28 for the accommodation of the steel tape or cable that extends from the winding drum of the sash balance to the sash and, in order that the strip 26 may be moved lengthwise from one position to another, an aperture 29 is formed in the inner portion of said strip and which aperture is accessible through a slot 30 that is formed in the underlying portion of the face plate.

This construction enables an implement, such as a nail set or the like, to be inserted in the aperture 29 for the purpose of moving the strip 26 inwardly or outwardly.

In the construction of some window frames, the ends of the lintels are extended so as to overlie the upper ends of the jambs and, where such construction is employed the ends of the face plates of the sash balance housing opposite the ends that are secured to the lintel rest upon the upper ends of the jambs or upon anchor plates that are applied to said upper ends.

Thus it will be seen that we have provided simple, practical and efficient means, whereby a spring sash balance housing may be easily and conveniently applied to the lintel of a window frame so as to function as a so-called overhead balance and which construction eliminates the necessity for installing the sash balances on the window jamb.

A particular advantage of our improved construction is, that the cable or flexible metal tape that is carried by the drum of the sash balance maintains a practically straight line between the periphery of the drum and the lower corner or side of the sash to which said cable or tape is connected and, such arrangement enables the cable or tape to pass onto and from the drum without frictional contact with any portion of the sash balance housing.

Further, our improved construction provides for a very firm and substantial anchorage for the sash balance housing in its overhead position, for one end of the face plate of the housing is firmly secured to the lintel and the other end of the face plate rests directly upon an anchor plate that is supported on the shoulder at the bottom of the mortise in the jamb that receives the end of the lintel.

It will be understood that minor changes in the size, form and construction of the various parts of our improved overhead spring sash balance, may be made and substituted for those herein shown and described, without departing from the spirit of our invention, the scope of which is set forth in the appended claims.

We claim as our invention:

1. The combination with a window frame jamb

and lintel, said jamb being mortised for the accommodation of the end of said lintel, said lintel being provided with an opening adjacent said jamb, and an anchor plate positioned on the shoulder at the lower end of the mortise in the jamb, which anchor plate is provided in its upper surface with a recess, of a spring sash balance including a housing and face plate, which housing projects upwardly through the opening in the lintel with the face plate positioned against the under face of said lintel, means for securing the inner end of said face plate to the lintel and the other end of said face plate projecting beyond the housing and resting on said anchor plate in said recess.

2. The combination with a window frame jamb and lintel, which lintel is provided adjacent the jamb with an opening, there being a mortise formed in the jamb for the reception of the end of said lintel and an anchor plate resting on the shoulder at the bottom of said mortise, said anchor plate being provided in its upper surface with a recess, of a spring sash balance including a housing positioned in the opening in said lintel and extending upwardly therefrom, a face plate secured to the housing of the sash balance, which face plate is positioned against the under face of the lintel and a member secured to and projecting from the end of the sash balance housing adjacent said jamb and seated in the recess in said anchor plate.

3. The combination with a window frame jamb and lintel, which lintel is provided adjacent the

jamb with an opening, there being a mortise formed in the jamb for the reception of the end of said lintel and an anchor plate resting on the shoulder at the bottom of said mortise, of a spring sash balance including a housing positioned in the opening in said lintel and extending upwardly therefrom, a face plate secured to the housing of the sash balance, which face plate is positioned against the under face of the lintel and a member mounted for movement on the outer lower corner of the sash balance housing and adapted when moved outwardly from said housing to engage and rest upon said anchor plate and provide a support for that portion of the housing adjacent said jamb.

4. The combination with a window frame jamb and lintel, which lintel is provided adjacent the jamb with an opening, there being a mortise formed in the jamb for the reception of the end of said lintel and an anchor plate resting on the shoulder at the bottom of said mortise, said anchor plate being provided in its upper surface with a recess, of a sash balance housing face plate secured to the under side of the lintel below the opening therein, one end of which face plate is secured to the lintel inwardly from said opening, the other end of which face plate rests in the recess in said anchor plate and a spring sash balance housing secured to said face plate and projecting upwardly through the opening in said lintel.
